UNITED STATES PATENT OFFICE

EARL L. MARTIN, OF DES MOINES, IOWA

MEANS FOR SUPPORTING A SEPARATING HOPPER AS APPLIED TO PORTABLE MILLS

Application filed January 26, 1931. Serial No. 511,241.

This invention relates to improvements in means for supporting separating hoppers such as used in connection with portable feed mills, and relates particularly to means for adjustably mounting the hopper, whereby the hopper may be easily and quickly elevated and lowered, and at the same time provides means whereby the hopper is firmly supported in either an elevated or lowered position.

More specifically it is the object of my invention to provide an improved support or stand for carrying a separating hopper which is of simple construction and formed principally of structural steel, and in such a manner that the parts are firmly secured together against working loose as the mill is moved from one position to another.

A further object is to provide improved means for securing the hopper to the movable member of the adjustable support.

A further object is to provide improved means for bracing the hopper after it has been moved to either of its adjusted positions.

A further object is to provide a simple and strong adjustable stand formed of structural angle iron having a stationary member and a movable member with simple and effective means for elevating and lowering the movable member.

My invention consists in the construction, arrangement and combination of the various parts of the device, whereby the objects contemplated are attained, as hereinafter more fully set forth, pointed out in my claims, and illustrated in the accompanying drawing, in which:

Figure 1 illustrates a portion of one end of a mill supporting frame showing the manner in which my improved hopper supporting stand is applied thereto.

Figure 2 is a top view of the same.

Figure 3 is an enlarged, detail, sectional view taken on the line 3-3 of Figure 1.

Figure 4 is an enlarged, detail, sectional view taken on the line 4-4 of Figure 2.

Figure 5 is an enlarged, segmental, sectional view taken on the line 5-5 of Figure 1.

Referring to the accompanying drawing, I have used the reference numeral 10 to indicate a supporting frame on which a mill 11 of ordinary construction is mounted. An engine 12 is also mounted on the frame for supplying power to the mill.

Adjacent to one side of the mill 11 is a blower 13, also driven from the engine 12, and designed to receive material from the mill as it is ground. Said material is delivered to a hopper 14 of ordinary construction. The lower end of the hopper is substantially funnel shaped, while the upper portion 15 of the hopper is of cylindrical formation. A pipe 16 connects the blower 13 with the member 15, in the usual manner, so that material delivered to the blower 13 will in turn be delivered to the hopper 14.

For supporting the hopper 14 I have provided an adjustable stand comprising an upright angle iron 17 having its lower end welded in one of the corners of the frame 10. One of the flanges 18 of the angle 17 lies adjacent to the inner surface of the side member of the frame, and the other flange 19 adjacent to the back member 20 of the frame. Supported adjacent to the outer surfaces of the flanges 18 and 19 and near their lower ends, and immediately above the frame member 10, is a bar 21, secured in position by welding and has its ends projecting inwardly, as clearly illustrated in Figure 5. The inwardly projecting ends are indicated by the numeral 22.

Supported near the upper end of the angle 17 is a bar 23 similar to the bar 21, having forwardly extending portions 24. A crank shaft 25 is rotatively mounted in the members 24, said shaft carrying a sprocket 26. The forwardly extending portions 22 have a shaft 27 designed to support a sprocket wheel 28. Mounted on the sprockets 26 and 28 is a chain 29, the purpose of which will hereinafter be made clear.

The free edges of the flanges 18 and 19 are provided with strap irons 30 welded in position and bent inwardly to form hook portions 31. Similar straps 32 are provided intermediate the upper and lower ends of the free edges of said channels,

- similar to the members 30. Said hook portions 31 provide guides for a movable angle iron 33 mounted inside of the angle 17 in the manner clearly illustrated in Figure 3.
- 5 The outer surfaces of the flanges 34 of the angles 33 are provided with blocks 35, to serve as spacers to permit the outer corners of the angle 33 from engaging the fillet of the angle 17.
- 10 By this arrangement it will be seen that the angle 33 is free to slide upwardly and downwardly in the angle 17. The angle 33 is connected to the inner run of the chain 29 by means of a block 36 in such a manner that as the chain 29 is rotated, the angle 33 will be moved upwardly and downwardly. The outer run of the chain 29 is provided with a stop member 37 designed to engage the sprocket 28 when the angle 33 has 15 reached its upper limit of movement. The angle 33 is locked against downward movement by means of suitable set screws 38 mounted in the flanges 18 and 19. The crank shaft 25 is provided with a crank 39 for operating the chain 29.

A brace bar 40 is welded to one side of the flange 19 near its upper end, and has its lower end connected to one of the frame members 10. A similar brace bar 41 is secured to the outer surface of the angle 18 and to the frame member 20. Said brace bars support the angle 17 in an upright position, and also the flanges 18 and 19 against torsional movement about the longitudinal axis of the angle.

Secured to the upper end of the flange 33 is a bracket plate 42 having rearwardly and outwardly extending portions 43. Bands 44 are provided for the upper and lower 40 ends of the member 15, the ends of said bands being secured together by means of a bolt 45 projecting through suitable lugs 46.

Mounted between the inner edges of the bands 44 is a plate 47 welded or otherwise 45 rigidly supported between the inner edges of said bands. The plate 47 and the bands 44 are secured to the members 43 by welding, so that the bracket 42, the plate 47, and the bands 44 form a unitary frame member for 50 clamping the upper end of the hopper 14, and provide means whereby the hopper may be easily and quickly removed if so desired for repairs or the like, by simply loosening the bolts 45, permitting the ends of the bands 44 to be separated sufficiently to allow the hopper to be removed.

The bands 44, the plate 47 and the bracket 42 provide means for rigidly supporting the hopper to the upper end of the 60 movable supporting member 33.

To assist in supporting the weight of the hopper and to assist in preventing swinging of the hopper about the longitudinal axis of the member 33, I have provided a telescoping brace member 48, one end of which

is pivotally connected to one of the frame members 10, and the opposite end pivotally connected to the lower band 44. A pin 49 is provided for locking the movable members of the brace in its various extended 70 positions. Suitable openings 50 are provided in the brace members for the pin 49.

By this arrangement it will be seen that I have provided a support for separating 75 hoppers, especially designed to be used in connection with portable mills, and formed principally of structural steel having all of its fixed members rigidly supported together by welding, to prevent loosening of the connections between the members due to excessive vibrations as the machine is moved from one position to another over rough ground.

Furthermore, I have provided means whereby the hopper may be easily and quickly adjusted to various elevations as desired in the operation of the machine, and provided with an adjustable brace for rigidly supporting the hopper in said adjusted 80 positions.

I claim as my invention:

1. The combination of an upright support, a second upright support slidably mounted longitudinally of the first support, a supporting frame comprising a pair of parallel 95 annular frame members, and a plate adjoining a portion of the inner edges of said frame members, and a bracket plate fixed to said plate and said annular members, said bracket being permanently fixed to the upper end of said second support.

2. The combination of a frame, an upright support, a second upright support slidably mounted longitudinally of the first support, means for elevating and lowering said second support, a supporting bracket fixed to the upper end of said second support, a telescopic brace having one end pivoted to one side of said supporting bracket and its other end pivoted to said frame, and means for locking the movable members of said brace to each other and in one of a number of adjusted positions.

3. The combination of a rectangular frame, an angle iron supported vertically from one corner of said frame, a brace member connected to the outer surface of each flange of said angle near its upper end, one of said braces being connected to one of the side members of said frame and the other to one of the end members of said frame, a second angle slidably mounted longitudinally of the first angle, guides carried by the first angle for slidably supporting the second angle, a laterally projecting supporting 115 bracket fixed to the upper end of the slideable angle, a telescopic brace member having one end pivotally connected to one side member of said bracket and its opposite end to the corresponding side member of said 120 125 130

supporting bracket to prevent swinging movement of said supporting frame about the longitudinal axis of said supports.

4. In a device of the class described, the 5 combination of an upright support, a second upright support mounted to slide longitudinally of the first support, an annular supporting bracket permanently fixed to the upper end of the last said support, means 10 for elevating and lowering said second upright, a telescopic brace having one end pivoted to said bracket and its opposite end pivoted to said frame, and means for fixing one member of said brace to the other member 15 at various adjusted positions.

5. In a device of the class described, the combination of an upright support, a second upright support mounted to slide longitudinally of the first support, a supporting 20 bracket fixed to the upper end of said second support, means for elevating and lowering said second support, means for locking the last said means at various elevated positions, a telescopic brace having one end 25 pivotally connected to said bracket and its opposite end pivotally connected to said frame, and means for fixing said brace members relative to each other at various adjusted positions.

30 6. The combination of an upright support, a second upright support slidably mounted longitudinally of the first support, a supporting frame comprising a pair of parallel annular frame members, a plate adjoining 35 a portion of the inner edges of said frame members, and means for fixing said plate to the upper end of said second support.

EARL L. MARTIN.
